UNITED STATES PATENT OFFICE.

HARRY WALKER, OF OIL CITY, LOUISIANA, ASSIGNOR, BY DIRECT AND MESNE ASSIGNMENTS, TO NATIONAL MANUFACTURING COMPANY OF AMERICA, OF OIL CITY, LOUISIANA, A CORPORATION OF DELAWARE.

VALVE FOR AUTOMATIC MUSICAL INSTRUMENTS.

Application filed May 29, 1926. Serial No. 112,717.

The present invention relates to a valve for automatic means for playing musical instruments such, for instance, as organs.

The object of the invention resides in the provision of a valve which is durable, inexpensive to manufacture, positive in its action, compact and convenient, not likely to easily become out of order, exceedingly efficient and reliable in operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Fig. 1 is an elevation of an assembly showing the manner in which one of my valves is used,

Fig. 2 is a sectional view taken substantially on the line 2—2 of Fig. 1, looking downwardly,

Fig. 3 is a section taken substantially on the line 3—3 of Fig. 1,

Fig. 4 is a section taken substantially on the line 4—4 of Fig. 3,

Fig. 5 is a section taken substantially on the line 5—5 of Fig. 3,

Fig. 6 is a section taken substantially on the line 6—6 of Fig. 3,

Fig. 7 is a plan view of one of the valves shown attached directly to a bellows, and

Fig. 8 is a sectional elevation of another assembly showing a further use of the valve.

Referring to the drawing in detail, it will be seen that the casing of the valve is formed in two parts preferably constructed of wood, the larger part being in the form of a block 5 which has a vertical bore 6 extending centrally therethrough, the lower portion of which is counterbored to be larger as at 7 and the lower portion of the counter bore 7 is further enlarged as is indicated at 8. A passage 9 extends transversely thru one end of the block 5 and at its intermediate portion communicates with a depending passage 10, the lower end of which is offset inwardly in the form of a channel, as is indicated at 11, communicating with the counter-bore 8. A passage 12 extends from one side of the block inwardly the inner end

thereof being curved downwardly to communicate with the counter-bore 7. A passage 13 extends inwardly from the other side of the block and is curved upwardly to open out through the top of said block.

A branch 14 is provided in the block 6 which, as is clearly shown in dotted lines in Fig. 5, opens thru the other side of the block, that is the same side through which the passage 12 opens. A cap 16 completes the valve casing, being constructed with the recess 17 and central opening 18 communicating with said recess, and registering with the bore 6. This cap 16 is glued onto the top of the block 5. A flexible diaphragm 20 in the form of a disk has its peripheral edge secured in the top of the bore 8 to separate the bores 7 and 8. A non-flexible or rather substantially non-flexible disk 21 is centrally located on the upper surface of the diaphragm 20 and is secured thereto by glue or in any other suitable manner.

A squared shank 22 is movable through the bore 6 and has its upper end attached to a strip of flexible material 23 preferably sheep skin, on the upper surface of which is fixed a substantially non-flexible disk 24 having a disk 25 glued to the upper surface thereof, said disk 25 being preferably sheep skin. These disks 24 and 25 are co-axially alined with opening 18 and bore 6. The ends of the sheep skin strip 23 are fixed by glue as at 27 between the block 5 and the cap 6. The under surface of the cap is cut away as at 28 for allowing proper flexing of the sheep skin strip 23.

A sheet of paper 29 or any other suitable material is pasted over the bottom surface of the block 5. A similar sheet of paper or the like 30 is pasted on the side of the block and the cap through which the passage 12 extends, this passage 12 registering with an opening 31 provided in the sheet 30 and an opening 32 provided in the vacuum board or chest 33. This paper is glued or pasted to the chest 33 and thus the valve is supported thereon.

The tube 34 leading to the bellows 35 communicates with the opening 13. The side of the block 5 on which is pasted the sheet 30 is provided with a channel 36 communicating with the adjacent end of the passage 9 with the passage 12 as is clearly shown in dotted line in Fig. 5. A reducer 37 is mounted in the

passage 9 adjacent the channel 36 and has a small opening 38 therein. The tracker bar tube 39 leading from tracker bar 40 communicates with the other end of the passage 9.

When the pump of the organ or the like is started in operation so as to create a vacuum in the chest 33 in the well known manner, and the tracker bar 40 is uncovered, 10 the valve will take the position shown in the drawing, since the suction through the passage 12 will raise the diaphragm 20 so as to close the disk 25 over the opening 18, and this suction will continue through the 15 bore 6, recess 17, and passage 13, to cause the collapsing of the bellows 35. When a record is placed over the tracker bar so as to cover the openings thereof, it will be seen that the suction through the passage 12 will 20 be transmitted through the passage 36, through the opening 38, through the passage 9, through the passage 10, through the branch 11, for creating a vacuum in the bore 8, thereby pulling downwardly on the 25 diaphragm 20, so that the strip 23 will close the upper end of the bore 6, and thus air will rush in through the opening 18, into the recess 17, through the passage 13, through tube 34, and into the bellows 35, so that said 30 bellows may expand.

Whenever an opening in the record sheet comes over the corresponding opening in the tracker 40, it will be seen that the valve will operate to the position shown in the 35 drawing for the purpose of causing the collapsing of the bellows.

In Fig. 7, I have shown the bellows 35^a attached directly to the valve and in this instance, the open end of the passage 13 will 40 be closed and an additional passage 14^a will be formed communicating with the passage 14, said passage 14^a communicating directly with the bellows. Otherwise this embodiment operates identical with that shown and 45 described.

In Fig. 8, another embodiment has been shown, wherein the bellows tube 34^a communicates with the outer end of the passage 14 through an opening provided in the sheet 50 30 and extends through the interior of the chest 33 and communicates with a bellows 35^b which is mounted on the other side of the chest. The open end of the passage 13, of course, in this instance, will be also closed.

The present embodiments of the invention have been disclosed merely by way of example since in actual practice they attain the features of advantage enumerated as desirable in the statement of the invention and 55 the above description. It is to be understood that the invention is not limited to the specific details of construction, organization, and mode of operation herein described for purposes of illustration. On the contrary, 65 the invention may be variously modified

within the scope of the sub-joined claims, as will appear to those skilled in the art.

The important feature of this invention is in the sheep skin strip 23 which forms a valve and a guide that positively prevents 70 incorrect feeding in respect to the bore 6 and the opening 18. No matter what position these parts may get into when this valve is in operation, these parts must seat correctly because of the flexible strip 23. The common valves now in use do not provide a strip of this nature, because of wear the least jar- 75 ring of the valve sometimes turns the same so that it will no longer seat correctly. This improved feature overcomes this difficulty 80 entirely, because no jarring affects the efficient operation thereof. In the valves now in common use, warping takes place which interferes with the efficiency thereof. No warping can take place in my valve which 85 will interfere with the proper seating thereof, because of the sheep skin strips reinforced at the seating portion thereof with the substantially non-flexible or hard disk 90 24 having the sheep skin disks 25 thereon which engages with the inner surface of the cap 26 for closing the opening 18.

Having thus described my invention, what I claim as new is:—

1. A valve structure of the class described 95 comprising a block having a bore formed of an upper portion, an intermediate portion of larger diameter than the upper portion, and a lower portion of larger diameter than the intermediate portion, said block being pro- 100 vided with a passage adapted to be in communication with a vacuum source and entering the bore, said blocks being provided with a second passage disposed transversely of one end thereof and a third passage leading 105 downwardly from the second passage through the bottom face of the block, said bottom face being provided with a channel communicating with the third passage and the lower portion of the bore, a sheet fixed on 110 the bottom face and closing the lower end of the lower portion of the bore, a flexible diaphragm fixed at its edge in the upper end of the lower portion of the bore to close off the lower portion from the intermediate 115 portion of the bore, a shank movable thru the upper portion of the bore, a strip of flexible material having its ends fixed to the surface of the block and extending across the upper 120 end of the upper portion of the bore, a disk on the strip, a cap having an opening register- 125 ting with the bore and provided with a recess, said disk adapted to close the opening, the upper end of the shank being fixed to the strip, said block being provided with a fourth passage leading from the recess and adapted to be in communication with a bellows, one side of the block being provided 130 with a channel entering the first passage, and one end of the second passage, a reducer in

said end of the second passage, the other end of the second passage being adapted to communicate with a tracker bar, a sheet on said one side of the block having an opening registering with the first passage.

2. A valve structure of the class described comprising a block having a bore formed in an upper portion, an intermediate portion of larger diameter than the upper portion and a lower portion of larger diameter than the intermediate portion, said block being provided with a passage adapted to be in connection with a vacuum source entering the bore, said block being provided with a second passage transversely of one end thereof and a third passage leading downwardly from the second passage through the bottom face of the block, said bottom face being provided with a channel communicating with the third passage and the lower portion of the bore, a sheet fixed on the bottom face and closing the lower end of the lower portion of the bore, a flexible diaphragm fixed at its edge in the upper end of the lower portion of the bore to close off the lower portion from the intermediate portion of the bore, a disk on the upper surface of the central portion of said flexible diaphragm, a shank movable through the upper portion of the bore and having its lower end resting on said disk, a strip of flexible material having its ends fixed to the upper surface of the block and extending across the upper surface of the upper portion of the bore, a disk on the strip, a cap having an opening registering with the bore and provided with a recess, said last mentioned disk adapted to close

the opening, the upper end of the shank being fixed to the strip, said block being provided with a fourth passage leading from the recess and adapted to be in communication with a bellows, one side of the block being provided with a channel entering the first passage and one end of the second passage, a sheet over said side of the block having an opening registering with the first passage, and a reducer in said end of the second passage, the other end of said second passage being adapted to communicate with a tracker bar.

3. A valve structure of the class described including a block having a bore, a portion of which is counter-sunk to be of larger diameter, said counter-sunk portion being at one face of the block, a cap having a recess in one surface, and an opening entering the recess from the opposite surface, said cap being fixed to the opposite face of the block from that heretofore mentioned with the recess and opening in registry with the bore, the recess directly communicating with the bore at the end of the bore opposite to the counter-sunk portion thereof, a primary pneumatic in the counter-sunk portion of the bore, a valve in the recess, means extending through the bore connecting the pneumatic and the valve, said valve comprising a strip of flexible material having its ends anchored between the cap and the block, a disc on the center of said flexible strip, adapted to close the opening in the cap.

In testimony whereof I affix my signature.

HARRY WALKER.
